US0D1097154S

(12) **United States Design Patent** (10) **Patent No.:** **US D1,097,154 S**
(45) **Date of Patent:** **** Oct. 7, 2025**

(54) **PUPIL DILATING RING**

(71) Applicant: **Michael Reynard**, Santa Monica, CA (US)

(72) Inventor: **Michael Reynard**, Santa Monica, CA (US)

(**) Term: **15 Years**

(21) Appl. No.: **29/891,199**

(22) Filed: **May 2, 2023**

(51) LOC (15) Cl. **24-02**

(52) U.S. Cl.

USPC **D24/150**; D24/135

(57) **CLAIM**

The ornamental design for a pupil dilating ring as shown and described.

DESCRIPTION

FIG. 1 is a top view of the invention;

FIG. 2 is a bottom view thereof;

FIG. 3 is a front view thereof;

FIG. 4 is a back view thereof;

FIG. 5 is a left side view thereof;

FIG. 6 is a right side view thereof; and,

FIG. 7 is a perspective view thereof.

1 Claim, 2 Drawing Sheets
